UNITED STATES PATENT OFFICE

156,584

JEWELRY BOX

Samuel Tylon, Cleveland, Ohio

Application September 9, 1948, Serial No. 148,515

Term of patent 14 years

(Cl. D58—11)

To all whom it may concern:

Be it known that I, Samuel Tylon, a citizen of the United States of America, residing at Cleveland, in the county of Cuyahoga and State of Ohio, have invented a new, original, and ornamental Design for Jewelry Box, of which the following is a specification, reference being had to the accompanying drawing, forming a part thereof.

In the drawing:

The dotted lines shown in the drawing are for illustrative purposes only.

I claim:

The ornamental design for a jewelry box, as shown and described.

SAMUEL TYLON.
